United States Patent Office

Des. 193,077
Patented June 19, 1962

193,077

WATER CRAFT

Richard G. Gorman, 741 Ocampo Drive, Pacific Palisades, Calif., and Robert E. Marsh, 11542 Foster Road, Los Alamitos, Calif.

Filed Sept. 12, 1961, Ser. No. 66,701

Term of patent 14 years

(Cl. D71—1)

FIG. 1 is a perspective view of a water craft showing our new design;

FIG. 2 is a side elevation of the water craft show in FIG. 1;

FIG. 3 is a front elevation of said craft;

FIG. 4 is a rear elevation thereof; and

FIG. 5 is a section taken along the line 5—5 of FIG. 2. We claim:

The ornamental design for a water craft, substantially as shown.
